DESIGN FOR A TILTER FOR VENETIAN BLINDS OR SIMILAR ARTICLE

Jules Nisenson, New York, N. Y., assignor to Unit
Venetian Blind Supply Co., New York, N. Y.,
a corporation of New York

Application October 18, 1938, Serial No. 80,525

Term of patent 3½ years

To all whom it may concern:

Be it known that I, Jules Nisenson, a citizen of the United States of America and resident of New York city, county of New York, and State of New York, have invented a new, original, and ornamental Design for a Tilter for Venetian Blinds or Similar Article, of which the following is a specification, reference being had to the accompanying drawing, forming part thereof.

In the drawing:

Fig. 1 is a front elevation of a tilter for Vene-

tian blinds showing my new design; Fig. 2 is a right side elevation; Fig. 3 is a rear elevation; Fig. 4 is a bottom plan view; Fig. 5 is a left side elevation; Fig. 6 is a view taken similarly to Fig. 1, with the cord guard element in an altered position thereof; and Fig. 7 is a view in perspective.

I claim:

The ornamental design for a tilter for Venetian blinds or similar article, as shown and described.

JULES NISENSON.
